United States Patent Office

Des. 180,326
Patented May 21, 1957

180,326

FORK OR SIMILAR ARTICLE

Richard Gavette, Southington, Conn., assignor to Wallace Silversmiths, Inc., Wallingford, Conn., a corporation of Connecticut

Application November 14, 1956, Serial No. 43,756

Term of patent 14 years

(Cl. D54—12)

FIG. 1

FIG. 2

FIG. 3

FIG. 4

FIG. 5

FIG. 6

Fig. 1 is a front view, in elevation, of a fork showing my new design;

Fig. 2 is a rear elevational view thereof;

Fig. 3 is a side elevational view thereof;

Figs. 4 and 5 are sectional views taken on lines 4—4 and 5—5, respectively, of Fig. 1; and

Fig. 6 is an enlarged view of the portion of the handle shown in Fig. 1 between dot and dash lines A—A and B—B.

I claim:

The ornamental design for a fork or similar article, substantially as shown.
